(57) **CLAIM**

The ornamental design for a cover of a fluid control valve assembly for fire protection systems, as shown and described.

DESCRIPTION

FIG. 1 Is A Front Perspective View Showing a cover of a fluid control valve assembly for fire protection systems In Accordance With A First Embodiment Of Our New Design; FIG. 2 Is A Front View thereof; FIG. 3 Is A Left Side View thereof; FIG. 4 Is A Right Side View thereof; FIG. 5 Is A Top View thereof; FIG. 6 Is A Bottom View thereof.

FIG. 7 Is A Front Perspective View Showing a cover of a fluid control valve assembly for fire protection systems In Accordance With A Second Embodiment of Our New Design;

FIG. 8 Is A Front View thereof; FIG. 9 Is A Left Side View thereof; FIG. 10 Is A Right Side View thereof; FIG. 11 Is A Top View thereof; and, FIG. 12 Is A Bottom View thereof.

The Back View of each of the First and Second Embodiments does not constitute part of the claimed design.

The shading lines in the drawings show contour and are not intended to indicate surface ornamentation.

1 Claim, 8 Drawing Sheets
